PAUL J. SIMMEN, OF EDEN, NEW YORK

AUTOMATIC TRAIN CONTROL

Refiled for abandoned application Serial No. 624,691, filed March 13, 1923. This application filed June 30, 1928. Serial No. 289,575.

This invention relates to railway train control, especially to train control systems in which a track circuit is employed to automatically control the train and more particularly systems in which in addition to the automatic control there is also a manual control.

In the modern operation of railways, it is found desirable to not only provide signals for the safe movement of trains but also to provide signals for use in facilitating the movement of trains. This invention provides for three signals under the control of the dispatcher, two of which may be used for safety and one for facilitating train movement; at the same time the dispatcher's control of the several signals is subject to automatic control by a track circuit. This invention is particularly adapted for single track railways over which trains operate in both directions, and in order that the dispatcher may intelligently use the several signals for the safe and quick direction of train movements, means are provided to automatically indicate or record at the dispatcher's office the progress of trains over the division.

Other objects and advantages will appear as the description of the invention progresses and the novel features will be particularly pointed out in the appended claims.

In describing the invention in detail, reference is had to the accompanying drawings, wherein I have illustrated a physical embodiment of my invention and wherein like characters of reference designate corresponding parts throughout the several views and in which:

Figure 1 is a schematic view of the apparatus and circuits in the dispatcher's office and along the track;

Figure 2, represents the apparatus and circuits on a locomotive or car.

Fig. 1 shows a single track consisting of rails 1 and 2; rail 1 is electrically continuous. Rail 2 is divided into sections by means of insulating joints as 3, thus dividing the track into block sections as A, B, C, D, E and F. In blocks B, D and F are shown sidings as 4 where trains can meet and pass each other.

At the clearance point of the siding, insulat-

ing joints as 3 electrically separate the straight portion of the siding from the main track. A track battery as 5 is located at one end of each block and track relays as b, c, d, e and f, near the other end of the block, constitute with their connections to the rails, the well known closed track circuit. Each track relay controls two armatures as 6 and 7. When the track relay is energized, armature 6 closes the front contact as 8 and armature 7 closes the front contact as 9, and when the track relay is deenergized, front contacts 8 and 9 are broken and armature 7 closes a back contact as 10.

Adjacent to the track are located groups of train control rails as 11 and 12, 13 and 14, 15 and 16 and 17 and 18. Train control rails 11 and 12 govern a west bound movement of a train from block E into D; train control rails 13 and 14 govern the west bound movement of a train from block D into C; train control rails 15 and 16 govern an east bound movement of a train from block C into block D; and train control rails 17 and 18 govern an east bound movement from block D into block E. Train control rails for west bound movements are on one side of the center line of the track and train control rails for east bound movements are on the other side of the center line of the track. With this arrangement, the train control rails are always on the right hand side of the direction in which the train is moving.

In each group of train control rails, one is the home train control rail located near the entrance to a new block, and the other is a distant train control rail, located approximately the braking distance from the entrance to the new block, thus train control rails 12, 14, 16 and 18 are home train control rails; and train control rails 11, 13, 15 and 17 are distant train control rails. These train control rails are of the usual construction having inclined ends or ramps, as shown in my prior Patent No. 1,140,623 granted May 25, 1915, and are so located along the track and insulated from the track, that a contact shoe attached to a locomotive or car can make electrical contact with them.

The four groups of train control rails 11

and 12, 13 and 14, 15 and 16 and 17 and 18 may all be positively energized or negatively energized or deenergized depending upon the position of the manually operable switch as 19 in the dispatcher's office, and these four groups of train control rails are duplicated at each siding where trains may pass each other.

When a train control rail is charged with positive direct current it is conditioned to give 10 a certain signal, when a locomotive is passing a train control rail; when a train control rail is charged with negative direct current, another or second signal is displayed on the locomotive when it passes the same; and when a 15 train control rail is deenergized, still another or third signal is displayed on the locomotive when it passes the same. The electrical energy to charge the train control rails is furnished from electrical sources such as batteries, 20 located at the dispatcher's office, interlocking tower or wayside station. When manually operated switch 19 in the dispatcher's office makes contact with spring contact as 20, the four groups of train control rails are charged 25 with positive direct current through a circuit as follows: from positive pole of battery 22, bus 23, wire 24, spring contact 20, manually operable switch 19, wire 25, relay 26, line wire 27, to a terminal 28, and from this terminal 28, a branch circuit is completed to train control rails 11 and 12 as follows: from terminal 28, wires 29 and 30, armature 7 of track relay *d*, wire 31, to train control rails 11 and 12. A 30 second branch circuit is also established to train control rails 13 and 14 as follows: from terminal 28, wires 29 and 32, armature 7 of track relay *c*, front contact 9 and wire 33 to train control rails 13 and 14. A third branch 35 circuit is also established to train control rails 15 and 16 as follows: from terminal 28, wires 29 and 30, armature 6, of track relay *d*, contact 8, and wire 34, to train control rails 15 and 16. A fourth branch circuit is also established to train control rails 17 and 18 as follows: from terminal 28, wire 35, armature 6 of track relay *e*, front contact 8, and wire 36 to train control rails 17 and 18.

When the manually operated switch 19 in the dispatcher's office makes contact with 50 spring contact 21, the train control rails are charged with negative direct current through a circuit as follows: from the negative side of battery 37, bus 38, spring contact 21, switch 19, wire 25, relay 26, line wire 27, to terminal 28, and thence through the four branch circuits heretofore described to train control rails 11 and 12, 13 and 14, 15 and 16 and 17 and 18. This last mentioned circuit being traced against the flow of current.

When the manually operated switch 19 in the dispatcher's office is in the vertical position so as to disconnect from both spring contacts 20 and 21, the four groups of train control rails are deenergized.

In addition to the train control rails being

electrically conditioned by the position of the manually operated switch 19 in the dispatcher's office, automatic control of the electrical conditions is provided by means of a track circuit, so that irrespective of the position of the switch 19, train control rails are deenergized, thus conditioning them to display the third signal on the locomotive, if the block ahead is occupied by another train. For instance, if there is a train in block D as shown in hatched lines, current from track battery 5 of block D is short circuited through the wheels and axles of the train, in a manner well known to those skilled in the art which results in armatures 6 and 7 of track relay *d* dropping away from front contacts 8 and 9, thus breaking the circuit to train control rails 11 and 12 and 15 and 16. Thus when block D is occupied, train control rails 11 and 12 and 15 and 16 which are guarding the entrance to block D from either end, are deenergized, and are therefore conditioned to display the third signal on the locomotive as hereinafter described. When there is a train in block C, track relay *c* is similarly deenergized and armatures 6 and 7 of track relay *c*, drop away from front contacts 9 thus breaking the circuit to train control rails 13 and 14, and 17 and 18 which are guarding the entrance to block C from either side.

I will now describe the apparatus and circuits on the locomotive or car, capable of displaying three different signals when a train control rail is positively energized or negatively energized or deenergized, and how the particular signal received at a train control rail is continued until the next train control rail is encountered.

Fig. 2 shows the apparatus and circuits on the locomotive and are similar to those shown in my prior Patent, No. 1,239,049 granted September 4, 1917. Three devices are shown in Fig. 2 and designated as No. 1, No. 2 and No. 3. While these devices are herein described as lamps, they may equally well be considered an electro-magnetic device to which motion is given depending upon whether the circuit is energized or deenergized. Such electro-magnetic devices may be used for other purposes, than, or in addition to, the display of signals to the engineer, such as is well known in the art; the proper control of speed control devices or electro-pneumatic air valves or both.

In Fig. 2 is shown an electric contact shoe 39 so positioned on the locomotive as to make contact with the train control rails. The contact shoe is hinged at 40. The train control rails are inclined at the end so as to form a ramp in the usual manner and when the contact shoe slides along this ramp, the shoe is tilted so as to break contact as 41. This motion of the contact shoe compresses a spring as 42. When the contact shoe leaves the other end of the train control rail, spring 42 forces

the contact shoe to the normal position, thus again making contact with contact 41. The locomotive also carries a polarized relay as 43, and a battery as 44. The polarized relay 43 controls a neutral armature 45 and three polarized armatures 46, 47 and 48. When relay 43 is energized, neutral armature 45 makes contact with front contact 49 and 50 and when the relay is deenergized, neutral armature 45 makes contact with back contact 51. When polarized relay 43 is positively energized, polarized armatures 46, 47 and 48 are in the right hand position as shown in Fig. 2, and they make contact with contacts 52, 53 and 15 54 respectively. When polarized relay 43 is negatively energized, polarized armatures 46, 47 and 48 are in the left hand position, opposite to that shown in Fig. 2 and the armatures make contact with contacts 55, 56 and 20 57 respectively. Polarized armature 46 by its position controls the circuit through either signals 1 or 2. Polarized armatures 47 and 48 are members of a pole changing switch used for the purpose of changing the direction 25 of the flow of current from battery 44.

When a locomotive is passing train control rails which are positively energized, a circuit is established through battery 22 in the dispatcher's office as follows: from positive pole 30 of battery 22, bus 23, wire 24, spring contact 20, manually operated switch 19, wire 25, relay 26, line wire 27, terminal 28, wires 29 and 30, armature 7 of track relay D, front contact 9, wire 31, to train control rails 11 or 12 and thence through contact shoe 39 on the locomotive, wire 58, polarized relay 43, wires 59 and 60, wheel axle 61, and wheel 62, to track rail 1 and thence by wire 63, to the negative side of battery 22.

10 A similar circuit is established through battery 22 in the dispatcher's office when the locomotive is passing any other positively energized train control rail, constituting one of the four groups with the difference that 15 the particular branch circuit from terminal 28 to a particular group of train control rails is substituted as hereinbefore described.

When contact shoe 39 is in contact with a positively energized train control rail, polarized relay 43 becomes positively energized and armature 45 makes contact with front contacts 49 and 50 and polarized armatures 46, 47 and 48 assume the right hand position as shown in Fig. 2 thus making contact

55 with their respective contacts 52, 53 and 54. With this position of the armatures a circuit is closed through signal No. 2 as follows: from positive side of battery 44, wires 64 and 65, contact 53, polarized armature 47, wire 66, armature 45, front contact 49, wire 67, polarized armature 46, contact 52, wire 68, signal No. 2, wire 69, polarized armature 48, contact 54, wire 70, to negative pole of battery 44.

65 When the contact shoe 39 leaves the other

end of the positively energized train control rail, contact 41 again closes and a stick circuit is established through polarized relay 43 as follows: from positive pole of battery 44, wires 64 and 65, contact 53, polarized armature 47, wire 66, armature 45, front contact 50, wire 71, contact 41, shoe 39, wire 58, polarized relay 43, wires 59 and 72, polarized armature 48, contact 54, wire 70 to the other pole of battery 44. It will thus be 75 seen that signal No. 2 is continued after contact shoe 39 has left the train control rail, since the armatures of relay 43 are continued in the same position.

When a locomotive is passing train control rails 11 or 12, which are negatively energized a circuit is established through battery 37 in the dispatcher's office as follows: from positive pole of battery 37, wires 73 and 63, to track rail 1, and thence through car wheel 62, 80 axle 61, wires 60 and 59, polarized relay 43, wire 58, to contact shoe 39, and thence through train control rails 11 or 12, wire 31, front contact 9, armature 7, of track relay, wires 30 and 29, terminal 28, line wire 27, relay 26, wire 25, manually operated switch 19, spring contact 21, and bus 38, to negative pole of battery 37. 90

A similar circuit is established through battery 37, in the dispatcher's office when the locomotive is passing any other negatively energized train control rail constituting one of the four groups, with the difference that the particular branch circuit from the train control rail to terminal 28 to a particular group of rails is substituted as hereinbefore described. 100

When contact shoe 39 is in contact with a negatively energized train control rail, polarized relay 43 becomes negatively energized, armature 45 makes contact with front contacts 49 and 50 and polarized armatures 46, 47 and 48 assume the left hand position that is opposite to that shown in Fig. 2, thus making contact with their respective contacts 55, 56 and 57. With this position of the armatures, a circuit is closed through signal No. 1 as follows: from positive pole of battery 44, wire 64, contact 57, polarized armature 48, wire 69, signal No. 1, wire 74, contact 55, polarized armature 46, wire 67, front contact 49, armature 45, wire 66, polarized armature 47, contact 56, and wire 70 to the other side of battery 44. 110

When the contact shoe 39 leaves the other end of the negatively energized train control rail, contact 41 again closes and a stick circuit is established through polarized relay 43 as follows: from positive pole of battery 44, wire 64, contact 57, polarized armature 48, wires 72 and 59, polarized relay 43, wire 58, contact shoe 39, contact 41, wire 71, front contact 50, armature 45, wire 66, polarized armature 47, contact 56, and wire 70 to the other pole of battery 44. It will thus be 120 125 130

seen that signal No. 1 is continued after contact shoe 39 has left the train control rail, since the armatures of relay 43 are continued in the same position.

When a locomotive is passing a train control rail which is deenergized, the polarized relay 43 becomes deenergized and armature 45 will drop from front contact 49 and 50, thus breaking the circuit through signal No. 1 or No. 2, and make contact with back contact 51. With armature 45 in this position a circuit is established through signal No. 3 as follows: positive pole of battery 44, wires 64 and 65, contact 53, polarized armature 47, wire 66, armature 45, back contact 51, wire 75, signal No. 3, wire 69, polarized armature 48, contact 54, wire 70 to the other pole of battery 44.

When the contact shoe 39 leaves the other end of a deenergized train control rail, contact 41, of the stick circuit relay 43, is again closed but this stick circuit is now inoperative, since front contact 50 of armature 45 is now open. Thus signal No. 3 is continued until a train control rail is reached which is energized.

Thus depending upon the position of switch 19 in the dispatcher's office, the dispatcher is enabled to display any one of the three signals on the locomotive but signals No. 1 or No. 2 as displayed by the dispatcher, are annulled or made ineffective if there is a train in the block ahead, because the train control rails automatically become deenergized by the reason of the effect of the train circuit and invariably signal No. 3 is displayed.

In the operation of the system, signals No. 2 and No. 3 may be used to direct the movement of train safely, and signal No. 1 may be used for facilitating the movement of trains. Thus signal No. 2 may be used to designate a clear track ahead and signal No. 3 may be used as a danger signal indicating that the block ahead is occupied or that the dispatcher wants to indicate to the train crew to stop and report. Signal No. 1 being a facility signal, may be used for any purpose designated by the management of a railway such as an indication to train crew to take the siding at the next passing point and report.

In order for the dispatcher to intelligently direct the movement of trains over his division, it is necessary for him to have a definite knowledge of the progress the trains are making over the road and for this purpose, this invention provides means for reporting automatically train movements in the dispatcher's office which I will now describe.

In the dispatcher's office is a suitably mounted record sheet as 76, driven by a roller as 77 which in turn is driven by a shaft as 78. Shaft 78 receives motion from ratchet wheel 79. A pawl as 80 is pivotally connected to

armature 81 of electromagnet 82. When the electromagnet 82 is periodically energized, motion is given to ratchet wheel 79 and pawl 80. A spring as 83 normally pulls armature 81 to the right when magnet 82 is not energized. Electromagnet 82 is connected by wire 84 to a suitable, well-known, make-and-break device as 85, such for instance as that shown in my prior Patent No. 1,203,146, granted October 31, 1915, which make-and-break device is periodically operated by a clock as 86. When the circuit through the make-and-break device is closed, electromagnet 82 is energized through the following circuit: positive pole of battery 87, wires 88 and 89, electromagnet 82, wire 84, make-and-break device 85, wires 90 and 91, to the other pole of battery 87. The make-and-break device 85 is operated, say every five seconds, so as to give a slow and uniform motion to record sheet 76, through ratchet wheel 79 and pawl 80. The record sheet 76 is transversely divided into sections as 92, 93 and 94, each section representing two blocks along the track, and longitudinally the record sheet is divided into time lines, as that designated at 1 a. m., each line representing a one-minute interval. It will thus be seen that longitudinally the record sheet assumes a constantly changing position during the 24 hours of the day. Adjacent to the record sheet are located perforating magnets 95 and 96 controlling armatures as 97. Pivotedly attached to armature 97 is a perforating needle as 98 so positioned adjacent to the record sheet that when perforating magnets 95 and 96 are energized a perforation is made upon the record sheet.

The circuit through the perforating magnets are controlled by the position of the switch 19. Switch 19 is pivoted on a shaft as 99 and forming an integral part of the switch is a contact spring as 100. When switch 19 is turned on the shaft 99 to make-contact with spring contact 20, contact spring 100 will make contact with spring contact 101, thus closing the circuit through perforating magnet 96 at this point. When switch 19 is turned so as to make contact with contact spring 21, contact spring 100 will make contact with spring contact 102, thus closing the circuit through perforating magnet 95 at this point. The circuits through perforating magnets 95 and 96 are also closed at front contact 103 of armature 104 of relay 26. Relay 26 becomes energized and thus closes the circuits through perforating magnet whenever a block is occupied and switch 19 makes contact with either spring contacts 20 or 21. For instance, if there is a train in block D, as shown in hatched lines, the current from the track battery 5 is short circuited through the wheels and axles of the train and the armatures of track relay D assume the de-energized position.

Armature 7 will therefore close back contact 10. Under these conditions the relay 26 in the dispatcher's office becomes energized through circuit as follows: from positive pole 5 of battery 22, bus 23, wire 24, spring contact 21, switch 19, wire 25, relay 26, line wire 27, terminal 28, wires 29 and 30, armature 7 of track relay D, back contact 10, wire 105, track rail 1, and wire 63, to the other pole of battery 10 22.

The above described circuit is established when switch 19 is in contact with spring contact 20, that is, when the train control rails are positively energized. When switch 19 is 15 in contact with spring contact 21, that is, when the train control rails are negatively energized and a block is occupied by a train, a similar circuit is established and relay 26 is energized, except that the energy is now 20 furnished from battery 37.

When switch 19 is in contact with spring contact 21 and a train enters a block, the circuit through perforating magnet 95 is closed as follows: from positive pole of battery 87, 25 wires 88 and 106, metallic contact plate 107, bus 108, wire 109, perforating magnet 95, wire 110, spring contact 102, contact spring 100, wire 111, front contact 103, armature 104, wire 112, bus 91, to the other pole of battery 87. It will thus be noted that the circuit 30 through the perforating magnets 95 and 96 is taken through a circuit breaking device as 107, so that this circuit is periodically broken. This circuit-breaking device operates as 35 follows: metallic contact plate 107, is attached to armature 81 and insulated therefrom, and every time the electromagnet 82 becomes energized, which as hereinbefore stated is say every five seconds, the contacts 40 through wire 106 and bus 108 is closed through metallic plate 107. When the magnet 82 is deenergized, armature 81 is pulled to the right by a spring 83 and the circuit through the perforating magnets are broken.

45 By reason of this periodic breaking of the circuit, intermittently continuous perforation is made on the record sheet as long as relay 26 is energized, which continues to be energized as long as the train is occupying 50 the corresponding block. It will thus be seen that when a train enters a block and switch 19 is in contact with spring contact 21, perforating magnet 95 begins to perforate, thus 55 recording the exact time when the train enters the block and this perforating magnet continues to perforate until the train has left the block, thus recording the length of time the train remained in the block.

When switch 19 is in contact with spring 60 contact 20, the circuit through perforating magnet 96 is closed through contact spring 100 and spring contact 101 and when a train enters a block perforating magnet 96 will 65 commence to perforate through a circuit as follows: from positive pole of battery 87,

wires 88 and 106, metallic plate 107, bus 108, wire 109, perforating magnet 96, wire 113, spring contact 101, contact spring 100, wire 111, front contact 103, armature 104, wire 112, and bus 91, to the other pole of battery 70 87. Thus perforating magnet 96 will commence to perforate when a train enters a block and will continue to perforate as long as the train is in the block.

75 While in the preferred form of my invention I have shown recording means to give the dispatcher knowledge of the location and progress of trains. I do not wish to be restricted to the recording means shown. Any means automatically indicating at the dispatcher's office the location and progress of the trains may be considered an equivalent within the scope of my invention. For instance, the perforating magnets 95 and 96 may be indication lamps which are lighted 80 when their respective circuits are closed; thus visibly indicating the location and progress of the trains. On the perforating magnets 95 and 96 may be any form of electrical translating devices which indicate 85 90 when the circuits through them are closed; thus the position of armature 97 in itself may be a visible indication to the dispatcher of the location and progress of trains.

95 Although I have particularly described and illustrated one preferred physical embodiment of my invention and explained the principle and construction thereof, nevertheless I desire to have it understood that the form selected is merely illustrative, and does 100 not exhaust the possible physical embodiment of means underlying my invention. For instance fixed signals along the trackway may be substituted for or added to the cab-signals shown herein; such as are shown in my pending application Serial No. 278,568 filed May 17, 1928, without departing from the spirit and scope of the invention.

105 What is claimed is:

1. A train control and dispatching system 110 for railways comprising a series of single track sections divided into blocks, a track circuit for each block, passing sidings at intervals along the trackway to permit the passage of trains, one siding for each section, trains for operating in either direction over the single track sections, means for actuating three signals governing the movement of a train in one direction through a section, means for actuating three signals for governing 115 the movement of a train in the opposite direction through the section and two means for controlling the signal actuating means, one controlling means being manually operated at a central office, the other controlling means being operated by track circuits in 120 said section and an adjoining block of an adjacent section.

125 2. A train control and dispatching system 130 for railways comprising a series of single

- track sections divided into blocks, a track circuit for each block, passing sidings at intervals along the trackway to permit the passage of trains, one siding for each section, trains for operating in either direction over the single track sections, means for actuating proceed, caution, and danger signals for governing the movement of a train through each section, said actuating means being provided for each direction of train movement, a central office, a dispatching circuit between the central office and the section, and two means each including the dispatching circuit for controlling the signal actuating means, one controlling means being manually operated at the central office, and the other controlling means being automatically operated by track circuits in said section and an adjoining block of an adjacent section. 15
3. A train control and dispatching system for railways comprising a series of single track sections divided into blocks, a track circuit for each block, passing sidings at intervals along the trackway to permit the passage of trains, one siding for each section, trains for operating in either direction over the single track sections, means for actuating three signals governing the movement of a train in one direction through a section, means for actuating three signals for governing the movement of a train in the opposite direction through the section, two means for controlling the signal actuating means, one controlling means being manually operated at a central office, the other controlling means being operated by track circuits in said section and an adjoining block of an adjacent section, and means including said track circuits for indicating at the central office the location of a train. 20
4. A train control and dispatching system for railways comprising a series of single track sections divided into blocks, a track circuit for each block, passing sidings at intervals along the trackway to permit the passage of trains, one side for each section, trains for operating in either direction over the single track sections, means for actuating three signals governing the movement of a train in one direction through a section, means for actuating three signals for governing the movement of a train in the opposite direction through the section, two means for controlling the signal actuating means, one controlling means being manually operated at a central office, the other controlling means being operated by track circuits in said section and an adjoining block of an adjacent section, and means including said track circuits for indicating at the central office the location of a train in relation to said track section. 25
5. A train control and dispatching system for railways comprising a series of single track sections divided into blocks, a track circuit for each block, passing sidings at intervals along the trackway to permit the passage of trains, one siding for each section, trains for operating in either direction over the single track sections, means for actuating proceed, caution, and danger signals for governing the movement of a train through each section, said actuating means being provided for each direction of train movement, a central office, a dispatching circuit between the central office and the section, two means each including the dispatching circuit for controlling the signal actuating means, one controlling means being manually operated at the central office, and the other controlling means being automatically operated by track circuits in said section and an adjoining block of an adjacent section, and means including said dispatching circuit and said track circuits for indicating at the central office the location of a train. 30
6. A train control and dispatching system comprising a single track railway including a series of sections divided into blocks, a track circuit for each block, sidings at intervals along the trackway to permit the passage of trains, one siding for each section, trains for operating in either direction over the single track sections, means for actuating proceed, caution, and stop signals governing the movement of a train moving in either direction through a section, said signal actuating means being controlled by track circuit means of a preceding block to provide rear end protection from block to block and also providing head on protection for the single track sections, and two means for controlling the signals, one means being manually operated at a central office and the other controlling means being automatically operated by track circuits in said section and an adjoining block of an adjacent section. 35
7. A train control and dispatching system comprising a single track railway including a series of sections divided into blocks, a track circuit for each block, sidings at intervals along the trackway to permit the passage of trains, one siding for each section, trains for operating in either direction over the single track sections, means for actuating proceed, caution, and stop signals governing the movement of a train moving in either direction through a section, said signal actuating means being controlled by track circuit means of a preceding block to provide rear end protection from block to block and also providing head on protection for the single track sections, two means for controlling the signals, one means being manually operated at a central office and the other controlling means being automatically operated by track circuits in said section and an adjoining block of an adjacent section. 40

cating at the central office the location of a train.

8. A train control and dispatching system for railways comprising a series of single track sections divided into blocks, a track circuit for each block, passing sidings at intervals along the trackway, one siding for each section, trains for operating in either direction over the single track sections, a central office, a dispatching circuit from the central office to the sections, means adjacent each section for supplying electrical energy to a train, means on the train for displaying three distinctive signals in accordance with the character of energy supplied thereto, and two means for controlling the supply of energy, one controlling means comprising a switch at the central office for energizing the dispatching circuit, the other controlling means comprising track circuits in said section and an adjoining block of an adjacent section.

9. A train control and dispatching system for railways comprising a series of single track sections divided into blocks, a track circuit for each block, passing sidings at intervals along the trackway, one siding for each section, trains for operating in either direction over the single track sections, a central office, a dispatching circuit from the central office to the sections, means adjacent each section for supplying electrical energy to a train, means on the train for displaying three distinctive signals in accordance with the character of energy supplied thereto, two means for controlling the supply of energy, one controlling means comprising a switch at the central office for energizing the dispatching circuit, the other controlling means comprising track circuits in said section and an adjoining block of an adjacent section, and means for indicating at the central office the acceptance of a signal by a train.
